UNITED STATES PATENT OFFICE.

NATHAN SMITH, OF GARRISON, MONTANA.

CATTLE-GUARD FOR RAILWAYS.

No. 821,439.

Specification of Letters Patent.

Patented May 22, 1906.

Application filed February 14, 1906. Serial No. 301 047.

To all whom it may concern:

Be it known that I, NATHAN SMITH, a citizen of the United States, residing at Garrison, in the county of Powell and State of Montana, have invented new and useful Improvements in Cattle-Guards for Railways, of which the following is a specification.

This invention relates to cattle-guards for railways; and the object thereof is to provide a cattle-guard designed to be arranged on opposite sides of the rails of the track-bed so as to prevent the passage of cattle and, furthermore, to provide an effective surface guard, which will permit of repairs to the same without disturbing more than the tie which it is desired to replace or repair or one section of the guard.

The invention further aims to provide a cattle-guard designed for use in connection with road-beds and which shall be simple in its construction, strong, durable, efficient in its use, and comparatively inexpensive to set up.

With the foregoing and other objects in view the invention consists in the novel combination and arrangement of parts hereinafter more specifically described, and illustrated in the accompanying drawings, wherein is shown the preferred embodiment of the invention; but it is to be understood that changes, variations, and modifications can be resorted to which come within the scope of the claims hereunto appended.

In the drawings, wherein like reference characters denote corresponding parts throughout the several views, Figure 1 is a top plan view of a cattle-guard constructed in accordance with this invention and arranged in operative relation with respect to a railway-track bed, and Fig. 2 is a longitudinal sectional view of the cattle-guard.

Referring to the drawings by reference characters, 1 2 denote the track-rails, which are secured upon the ties 3 in a known manner, and interposed between the track-rails 1 2 is the intermediate section of the cattle-guard, and the said intermediate section comprises two series of guard-plates, the guard-plates of one series being slightly removed from the guard-plates of the other series, and the said two series of guard-plates are slightly removed from the inner face of the track-rails 1 2. Each of the guard-plates of each series comprises a vertically-extending portion 4 and an elongated flat portion 5, which extends at right angles with respect to the

portion 4. The vertically-extending portion 4 of each of the guard-plates of the intermediate section is secured by the holdfast devices 6 to one side of the tie in such a manner that the elongated flat portion 5 will extend above and over the tie and toward the vertically-extending portion 4 of the adjacent guard-plate. Owing to the manner of constructing and setting up the guard-plates of the intermediate section, the elongated portion 5 of each guard-plate becomes a spring member, so that when the cattle tread on the portions 5 they will descend; but owing to the length of said portions 5 the feet of the cattle will be prevented from being wedged between the elongated portion 5 of one guard-plate and the vertically-extending portion 4 of the adjacent guard-plate.

Secured to the ties 3 at each outer side of the track-rails 1 2 and in transverse alignment with the guard-plates of the intermediate section is a series of outer guard-plates 7, which are secured to the ties by the holdfast devices 8 and which are substantially of the same construction as the guard-plates of the intermediate section. Therefore it is thought unnecessary to specifically describe the guard-plates of the two outer series of guard-plates.

At both ends of each series of guard-plates protecting members 9, 10, and 11 are provided and which are adapted to prevent anything from the cars injuring the guard-plates. These members are secured by the holdfast devices 12 to the supports or ties 13. The protecting members 9, 10, and 11 are arranged in close proximity to the vertically-extending portion of the guard-plates, and the said members 9, 10, and 11 are beveled. The members 9, 10, and 11 are adapted to prevent anything dragging from the cars injuring the guard-plates.

Interposed between the ties 3 of the track-bed, to which the guard-plates are attached, are the filling members 19, which are secured in position in any suitable manner and are adapted to keep the ties 3 from shifting, thereby preventing any disarrangement of the guard-plates when the cattle-guard is set up in operative position.

It will furthermore be evident that a device constructed in a manner as hereinbefore described sets up a smooth surface guard and will not clog with snow under ordinary circumstances; but in case of any foreign matter, such as snow, getting under the plates or

the longitudinal section they are easily raised and the foreign matter removed. Furthermore, the plates can be readily kept in working order, and when the plates are in operative position they will prevent the animal from crossing the track-bed.

Having thus fully described my invention, what I claim as new, and desire to secure by Letters Patent, is—

- 10 1. A cattle-guard comprising an intermediate section consisting of two series of guard-plates, and two outer series of guard-plates, the guard-plates of each series consisting of a vertically-extending portion and a right-angled-extending portion.
- 15 2. A cattle-guard embodying an intermediate series of guard-plates and two outer series of guard-plates, each plate of each series of plates consisting of a vertically-extending portion and a right-angled-extending portion arranged over and extending from the tie to which said plate is secured, and means for securing the vertically-extending portions of the guard-plates to railway-ties.
- 20 3. A cattle-guard comprising an intermediate section consisting of two series of guard-plates, and two outer series of guard-plates, the guard-plates of each series consisting of a vertically-extending portion and a right-angled-extending portion, combined with beveled protecting members arranged at each end of each series of plates.
- 25 4. A cattle-guard embodying an intermediate section consisting of two series of guard-plates, and two outer series of guard-plates, the guard-plates of each series consisting of a vertically-extending portion and a right-angled-extending portion arranged over and extending from the tie to which said plate is secured, and means for securing the vertically-extending portions of the guard-plates to railway-ties.
- 30 5. A cattle-guard embodying an intermediate section consisting of two series of guard-plates, and two outer series of guard-plates, the guard-plates of each series consisting of a vertically-extending portion and a right-angled-extending portion arranged over and extending from the tie to which said plate is secured, and means for securing the vertically-extending portions of the guard-plates to railway-ties, combined with beveled protecting members arranged at each end of each series of plates, and means interposed between the ties to which the guard-plates are secured for preventing the spreading of the ties.

5. A cattle-guard embodying an intermediate section consisting of two series of guard-plates, and two outer series of guard-plates, each plate of each series of plates consisting of a vertically-extending portion and a right-angled-extending portion arranged over and extending from the tie to which said plate is secured, and means for securing the vertically-extending portions of the guard-plates to railway-ties, combined with beveled protecting members arranged at each end of each series of plates, and means interposed between the ties to which the guard-plates are secured for preventing the spreading of the ties.

In testimony whereof I have hereunto set my hand in presence of two subscribing witnesses.

NATHAN SMITH.
